UNITED STATES PATENT OFFICE

2,266,259

AIR CONDITIONING APPARATUS

Deane E. Perham, Chicago, Ill.

Application October 1, 1938, Serial No. 232,825

3 Claims. (Cl. 183—44)

My invention pertains to air conditioning apparatus and is particularly concerned with the provision of a unit adapted to be placed in the room of a dwelling or office building to heat, cool, humidify, dehumidify, circulate, cleanse, and/or replace the air therein.

An object of my invention is to provide a unit which is more compact and efficient than those now in use.

Another object is to provide an air conditioning unit which is simple and economical to make and which will give long trouble-free service.

Another object is to provide an air conditioning unit having a more efficient heating means than any heretofore used.

Another object is to provide an air conditioning unit which may have means for the direct radiation of heat into the room.

Another object is to provide improved means for directing the air against the heating and cooling elements for the purpose of promoting efficiency.

Another object is to provide an air conditioning unit having a more efficient cooling means than any heretofore used.

Another object is to provide improved means for cleaning and circulating air whereby the unit is prevented from becoming clogged with dirt and whereby the air in the room is maintained free from dust and dirt.

Another object is to provide a unit wherein the means for cleansing the air may be readily replaced at periodic intervals.

Another object is to provide a unit which is more adaptable for different sizes of rooms than any heretofore known.

Another object is to provide improved and more efficient means for moistening the air passing through the unit.

Another object is to provide improved control means whereby the unit may be more readily adapted to produce any desired atmospheric condition in the room in which it is located.

Another object is to provide an improved grouping of the controls for regulating the unit.

Another object is to provide a unit wherein all parts are readily accessible for adjustment or inspection.

Another object is to provide an improved unit which may be partially recessed in the wall of the room in which it is located.

Another object is to provide a unit having an improved frame construction.

Other objects and advantages will become apparent as the description proceeds.

The unit disclosed in this application is an improvement over the units disclosed in my prior applications, Serial No. 723,697 filed May 3, 1934, and Serial No. 89,148 filed July 6, 1936, now Patent No. 2,186,145, issued Jan. 9, 1940.

In the drawings:

Figure 1 is a longitudinal section taken on the irregular line 1—1 of Figure 2;

Figure 2 is a transverse section taken on the line 2—2 of Figure 1;

Figure 3 is a transverse section taken on the line 3—3 of Figure 1;

Figure 4 is a transverse section taken on the line 4—4 of Figure 1;

15 Figure 5 is a partial transverse section showing the control mechanism and is taken on the line 5—5 of Figure 1;

Figure 6 is a partial section showing the fresh air damper control mechanism and is taken on the line 6—6 of Figure 5;

Figure 7 is a further sectional view showing the fresh air damper control mechanism and is taken on the line 7—7 of Figure 1;

20 Figures 8 and 9 are diagrammatic views showing the electrical connections and automatic controls; and

Figure 10 is a horizontal section through a wall of a room illustrating the way in which my air conditioning unit may be recessed therein.

30 Referring to the drawings, I have illustrated therein a preferred embodiment of my invention wherein the operative parts of the apparatus are supported on a frame A comprising a box-like structure formed of sheet metal plates welded or otherwise suitably secured to each other. As shown most clearly in Figures 1 to 4 inclusive, this frame A comprises a front sheet 20 welded or otherwise suitably secured at its upper edge to the up-turned flange 22 of a top sheet 24 and

35 welded at its lower edge to the up-turned flange 26 of a metal sheet 28 which forms the bottom of the frame proper and which is also bent upwardly to form the back of the frame. The upper edge 30 of this combined bottom and back sheet 28 is welded to the upstanding flange 32 of the top sheet 24.

40 The ends of the box-like frame A are formed by end sheets 34 and 36 which are welded or otherwise suitably secured to flanges formed by over-

turning the end edges of the metal sheets 20, 24 and 28 heretofore referred to. The end sheet 34

45 has welded or otherwise suitably secured thereto, a pair of U-shaped supporting brackets 38 which are mounted on legs 40, the upper ends of

50 the legs being threaded as indicated at 42 and

55 the ends of the box-like frame A are formed by end sheets 34 and 36 which are welded or otherwise suitably secured to flanges formed by over-

turning the end edges of the metal sheets 20, 24 and 28 heretofore referred to. The end sheet 34

55 has welded or otherwise suitably secured thereto, a pair of U-shaped supporting brackets 38 which are mounted on legs 40, the upper ends of

provided with nuts 44 and 46 whereby the legs 40 may be adjusted to vary the height of the frame from the floor of the room in which it is located. The end plate 36 is similarly provided with a pair of U-shaped supports 48 in which the legs 50 are adjustably mounted in the same manner.

A pair of channel members 52 are welded or otherwise secured to the lower side of the top frame sheet 24 and each of these channel members has a laterally directed flange 54 forming a support for the base 56 carrying the electric motor 58 and fans 60 and 62 driven thereby. The base 56 simply rests upon the flanges 54 and may be secured in place by the cap screws 64 (Figure 2). A feature of my invention lies in the accessibility of the parts of my air conditioning unit for purposes of inspection, cleaning, and repair, and replacement, and I have accordingly provided means whereby the base 56, motor 58, and fan 60, may be readily removed.

Referring particularly to Figure 2, I have illustrated that portion of the sheet 28 which forms the front of the box-like frame A as being provided with an opening 66 which is normally closed by a removable cover 68. The cover 68 is made of sheet metal which is reversely bent at its lower end to provide a recess 70 for receiving the upstanding edge of the plate 28 when the cover is in place. The upper edge of the cover 68 is also reversely bent as indicated at 72, to receive the upstanding edge 74 formed from the top portion of the plate 28. It will be appreciated that the cover 68 may be readily removed to permit removal of the base 56 with its associated motor and fan units by merely unscrewing the cap screws 64 and withdrawing the base in a horizontal direction. After the desired inspection, cleaning, or repairing has been made, the base and its associated units may be as readily replaced and secured in position by the cap screws 64. The cover 68 can then be replaced. It will be noted that the motor 58 is supplied with current through a cord 76 having a separable connection 78 with facilitates such withdrawal and replacement of the motor and fan units.

The channel members 52 also provide as shown in Figure 1 means for holding in place the upper ends of filter elements 80 and 82, the lower ends of these elements being positioned in channel members 84 welded or otherwise secured to the plate 28 forming the bottom of the frame A. These filter elements 80 and 82 may be removed and replaced by simply removing the cover 68 and sliding the filter elements 80 and 82 from their positions in the channel members 52 and 84. New filter elements can then be inserted and the cover 68 replaced.

I shall now describe the manner in which the air is drawn into the interior of the frame A by the fans 60 and 62. Where the unit is to be used in a room requiring only a moderate amount of air circulation, all of the air supplied to the fans 60 and 62 passes through the filter units 80 and 82 and when the unit is so used, the bottom portion of the metal sheet 28 is imperforate. I shall first describe the air flow to the fans 60 and 62 as it occurs in such an installation.

The filter 80 is interposed between the fans and a compartment 86 formed in one end of the frame A. The compartment 86 receives air from the room through an opening 88 in the end plate 34 which connects the compartment 86 with the space between the frame A and a removable cover 90 which encloses the entire unit. This cover

has a large back opening 92 through which room air is readily admitted to the interior of the cover 90 since in making the installation the back of the cover 90 is spaced from the wall of the room sufficiently to permit a ready flow of room air into the back opening 92. Additional room air may enter the cover 90 through the lower front opening 94 and the lower end openings 96.

As best shown in Figure 7 the compartment 86 also communicates with the outside air through an opening 98 in the back panel 20 of the frame A and by way of duct 100 which extends through the building wall 102. The proportions of room air and fresh air admitted to the compartment 86 are controlled by a damper 104 pivoted at 106 and connected by pivoted link 108 to arms 110 of the control rod 112. A tension spring 114 connects the cotter pins 116 which form the pivotal connections for the link 108 and prevents rattling of the damper 104.

As best shown in Figure 5, the control rod 112 has a handle 118 at its upper end whereby the control rod 112 and damper 104 may be shifted to any desired position. The position of the damper is readily indicated by the indicia provided at the lower edge of a name plate 120 supported on an upright bracket 122 attached to one end of the frame A.

Referring particularly to Figures 5 and 6, it will be seen that a coil spring 124 has one end attached to the control rod 112 as indicated at 126 and a second end 128 resting against a portion of the bracket 122 in such manner that when the control rod 112 is turned to open the damper 104 and admit fresh air to the compartment 86, the tendency of the spring 124 is to close this damper. The damper and control rod are held in the desired position by a friction clutch comprising a clutch member 130 (Figure 6) pivoted at 132 and held in frictional engagement with the control rod 112 by a spring 134. When it is desired to close the damper 104 to exclude fresh air, it is only necessary to push on the button 136 attached to the clutch member 130 in the direction indicated by the arrow in Figure 6, whereupon the clutch member 130 will be moved out of engagement with the control rod 112 and the damper 104 will be closed by the spring 124.

The room air or mixture of room and fresh air entering the compartment 86 passes through the filter 80 and into the fan compartment. The fan compartment also receives room air through the filter 82 which communicates with the interior of the cover 90 by way of compartment 138 and opening 140 in end member 36.

Where my air conditioning unit is intended to be used in a room requiring a very large circulation of air, I find it desirable to provide additional filter means which I preferably provide by welding or otherwise suitably attaching a sheet metal compartment B to the lower side of frame plate 28 as clearly shown in Figure 1. When my air conditioning unit is so used, the frame plate 28 is provided with an opening 142 registering with an opening 144 in the top of the compartment B to connect the interior of this compartment with the compartment 86. The bottom plate 28 of the frame A is also provided with a second opening 146 adapted to register with the filter 148 mounted in the compartment B. This structure permits additional air to be drawn from compartment 86 through filter 148 and opening 146 into the fans 60 and 62.

In order to maintain the desired ratio between room air and fresh air supplied to the fans 60 and

62, I preferably divide the large filter 148 into two parts by means of a partition 150 attached to a long sleeve 152 slidable on a rod 154 extending longitudinally of the compartment B. That portion of the filter 148 to the left of the partition 150 receives its supply of air from the compartment 86 containing the damper 104 for regulating the proportions of fresh air and room air admitted thereto. That part of the filter 148 which is to the right of partition 150 as viewed in Figure 1 receives a supply of room air from the opening 155 in the right-hand end of compartment B.

In most installations where the compartment B is used, it will suffice to position the partition 150 at the time the installation is made. If a readily adjustable partition should be desired for any particular reason, the sleeve 152 and rod 154 may be threaded so that the partition 150 may be shifted by rotating the rod 154.

An evaporator plate C is supported on the box-like frame A and is insulated therefrom by an asbestos gasket 156. The plate C is preferably made of metal which conducts heat readily and this plate receives some heat from a pipe 158 which is brazed or otherwise suitably secured to the plate C and to which a heat conducting medium is supplied in a manner which I shall hereinafter describe. Water is supplied to the evaporator plate by way of pipe 160 (Figure 4), petcock 162, pipe 164, and valve 166 controlled by a float 168 which maintains a predetermined level of water overlying the evaporator plate C. This water comes directly in contact with the pipe 158 and receives heat directly therefrom.

The water admitted to the upper surface of plate C first flows into the end compartment 170 (Figure 1) and thence through an opening 172 to the central compartment of the plate C. A second opening 174 connects this central compartment with the other end compartment 176. In case the float controlled valve 166 should fail to cut off the supply of water when the proper level of water on the plate C is reached, any excess water will over-flow through the ports 178 in a tubular screw plug 180 threaded into the upper end of a sleeve-like portion 182 constituting an integral part of the plate C. The upper end of a drain pipe 184 is attached to the lower end of this sleeve-like portion 182 and carries away the excess water.

When it is not desired to operate the unit as a humidifying unit, the supply of water to the evaporator plate C is cut off either by manually operating the petcock 164 or by an electrically controlled valve located in the water supply line which I shall hereinafter describe. Under these conditions, means is preferably provided to drain from the upper surface of the evaporator plate C any moisture which may collect thereon. This is accomplished by rotating the tubular plug 180 through an angle of 180° to bring the hole 185 therein in registry with the drain opening 186, whereupon any moisture collecting upon the upper surface of the plate C may be carried away through this drain opening 186 and drain pipe 184. The upper end of the tubular plug 180 is provided with a cross-pin 188 to facilitate the adjustment of this plug to correspond with the intended operation of the unit.

The air discharged by the fan 60 passes upwardly through a flanged opening 190 in the evaporator plate C and into contact with a deflector 192. Similarly, the air discharged by the fan 62 passes upwardly through the flanged open-

ing 194 in the evaporator plate C and into contact with a deflector 196. The deflected air readily picks up any vapor given off by the heated water overlying the evaporator plate C prior to passing to the heating coils which I shall now describe.

Mounted upon the evaporator plate C is a second box-like frame D comprising end plates 198 and 200 and side plates 202 and 204. The end plates 198 and 200 have outwardly directed flanges which are bolted or otherwise suitably secured to the pedestals 206 which form an integral part of the evaporator plate C. The lower ends of the side plates 202 and 204 are reversely bent and are pressed into engagement with the inner surfaces of the side flanges of the evaporator plate C by guiding fingers 208 provided by the evaporator plate C.

The end plates of the box-like frame D support a plurality of heat exchange pipes which may be varied in number and arrangement for different installations. In the particular installation illustrated, there are eleven pipes, nine of which are used for cooling and two of which are used for heating. Each of these pipes is preferably made of aluminum or other non-corroding metal of high heat conductivity and comprises a central tubular portion surrounded by a plurality of generally radially directed spines which are integral with the material forming the tubular portion and which are struck up therefrom. As most clearly shown in Figure 2, the two heating pipes 210 and 212 are separated from the cooling pipes by a longitudinally extending vertical partition 214 having laterally directed ends 216 which are welded or otherwise attached to the end plates 198 and 200. Each flange 216 has a recess 218 adapted to receive the pipe 210 and thereby readily determine the position of the flange 214. A damper 220 is mounted on a rod 222 which extends longitudinally of the unit adjacent the upper edge of the partition 214 so that by rotating the rod 222 all of the air may be made to pass over the cooling elements or all of the air over the heating elements or any proportion of air over either group of elements. For this purpose I provide the rod 222 with a handle 224 and the name plate 120 is suitably marked to indicate at any time the position of the damper 220.

Steam, hot water, or other suitable heating medium is supplied to the evaporator pipe 158 and the heating pipes 210 and 212 through a heat supply pipe 226 (Figure 1) and is returned to the furnace through a heat return pipe 228. The particular piping connections may vary with the heating medium used. When the heating medium is steam, I preferably connect the piping so that the steam supplied through the pipe 226 passes first into the heating pipes 210 and 212 which are connected in parallel and flows from these pipes through the evaporator pipe 158 and is returned to the furnace. On the other hand, where hot water is used as a heating medium, I ordinarily prefer to connect the heating pipes 210 and 212 and the evaporator pipe 158 in parallel as indicated in the drawings. It will be understood that my air conditioning unit may also be provided with a heat radiating plate like the plate 308 of my said prior application, Serial No. 89,148. The quantity of heat supplied may be automatically regulated as I shall hereinafter describe.

In the embodiment illustrated in the drawings, a refrigerant is supplied to the cooling pipes through a refrigerant supply pipe 230 (Figure 1)

to an automatic expansion valve 232. The expanded refrigerant enters a header 234 connected to the left-hand ends of pipes 236, 238, and 240, whose other ends are connected to pipes 242, 244 and 246 respectively. The left-hand ends of these latter pipes are illustrated as discharging into a second header 248 which is connected to the left-hand ends of the three lower pipes 250, 252 and 254. A third header 256 connects the right-hand ends of these last-named pipes with a refrigerant return pipe 258.

In the installation illustrated in the drawings, the automatic expansion valve 232 is controlled by a bulb 260 held in contact with the lower side of the header 248 to regulate the quantity of refrigerant admitted to the cooling elements. Where cold water is used as a cooling medium, the automatic expansion valve 232 would be replaced by a flow control valve regulated by a bulb attached to the header 256. Various other modifications may be made to suit particular conditions.

It will be noted that the evaporator plate C is located beneath all of the heat exchange pipes so that any moisture which may collect thereon will drop onto the evaporator plate C and may be drained therefrom in the manner previously described when dehumidification is desired. The deflectors 192 and 196 prevent any moisture dripping from the heat exchange pipes from entering the housings of the fans 60 and 62. It will further be noted that the lower ends of the side plates and end plates of the frame D are so located that any moisture collecting thereon will fall into the evaporator plate C.

After passing over the heat exchange pipes and passing the damper 220, the air is discharged from the upper end of the box-like frame D through the outlet 262. This outlet registers with the grille 264 provided by the removable cover 90. This removable cover is not bolted or otherwise attached to the rest of the mechanism but is held in place solely by fingers 266 (Figure 2) which are attached to the front of the cover 90 and which slide in U-shaped channel members 268 secured to the front portion of the plate 28 adjacent the ends thereof. This construction makes it possible to completely remove and replace the cover 90 for inspection, cleaning, repair, or replacement of the mechanism enclosed therein without in any way disturbing the operation of this mechanism. The removable cover 90 is preferably provided with end doors 270 to permit ready access to the controls and valves.

A feature of my invention lies in the grouping and accessibility of the several controls. Referring particularly to Figure 5, it will be seen that I have provided a name plate 120 which is located adjacent the control handles for the dampers controlling the proportion of fresh air to room air and controlling the flow of air over the heat exchange pipes, and that this name plate carries indicia indicating at all times the positions of these dampers. This name plate may bear the name of the manufacturer or distributor and also carries the electrical control switches which are indicated as constituting a master control switch 272 for connecting the unit to or disconnecting it from the lighting circuit of the home or office in which the unit is located, a second switch 274 for regulating the speed of the fans, and a third switch 276 whose position determines whether the unit is to be used as a cooling unit, a heating unit, or merely an air circulating unit.

It will be noted that the name plate 120 and switches carried thereby are located alongside of a terminal block 278 for the various electrical connections. In Figure 8 I have diagrammatically shown the connections between the terminal block 278, the two wires of the house lighting circuit 280, the switches 272, 274, 276, and the fan motor 58.

In Figure 9 I have shown these same circuits 10 in combination with the various automatic electrical controls, the numbers 1 to 8 inclusive appearing on Figure 9 corresponding to the similarly numbered terminals on the block 278 of Figure 8. In Figure 9 the controls are indicated 15 as comprising a thermostat 282 controlling a solenoid valve 284 for shutting off the supply of refrigerant or other cooling medium when the room temperature drops to a predetermined point, a humidostat 286 controlling a solenoid valve 288 for cutting off the supply of water to the evaporator plate C when the air in the room attains a predetermined degree of humidity and 20 a thermostat 290 controlling a solenoid valve 292 for cutting off the supply of heat when the temperature in the room reaches a predetermined 25 maximum.

It will be understood that the automatic controls indicated in Figure 9 have been selected as typical and that my invention is not limited to 30 the particular arrangement of controls therein shown. Any or all of the automatic controls illustrated in Figure 9 may be dispensed with entirely or other types of automatic controls may be substituted therefor. A typical example of 35 such a substitution would be to use a bellows type heat control valve having its regulating bulb located in the air outlet 262. Numerous other substitutions will readily occur to those conversant with the art and the controls commonly 40 used therein.

Where my invention is to be installed in a building under construction, or in a building which is being remodeled, it may frequently be desirable to locate my air conditioning unit in a 45 recess formed in the wall for this purpose. In Figure 10 I have diagrammatically illustrated a typical installation of this type. In this figure I have illustrated an air conditioning unit 294 which may be identical with that previously described except that the removable cover 90 thereof has been omitted. This unit 294 is partially located in a recess 296 provided in the wall 298, a duct 300 being provided through the wall to admit fresh air to the unit. The front 50 of the unit, and that portion of the sides and top of the unit which project from the wall, are enclosed by a cover 302 having louvers 304 and 306 to admit room air to the back of the unit. I have provided my novel unit with the offset outlet 262 in order to make this unit particularly 55 adaptable for installation in wall recesses similar to the recess 296. It will be understood that the cover 302 has a grille similar to the grille 264 of the cover 90 located above the unit outlet 262.

60 My invention is not limited to the particular details illustrated and described herein, but may assume numerous and varied forms. The appended claims have, therefore, been drawn to cover the features specified therein, both in the 65 form shown in the drawings, and all variations thereof.

I claim:

70 1. In a device of the class described the combination of a box-like frame having top, bottom, and side portions forming an elongated enclo-

sure, filter elements dividing said enclosure into two end chambers and a center chamber, a box-like compartment located beneath said frame and secured thereto, there being an opening establishing communication between the interior of said box-like compartment and one of said end chambers, there also being a second opening establishing communication between the interior of said box-like compartment and said center chamber, a filter located between said compartment and said center chamber, there being openings connecting one of said end chambers with fresh air and the other of said end chambers with room air, a partition in said compartment, said partition being adjustable to vary the area of said last-named filter available for passage of fresh air therethrough, and a motor-driven fan located in said center chamber, said fan receiving its supply of air through said filters.

2. In a device of the class described, the combination of a box-like frame having top, bottom, and side portions forming an elongated enclosure, filter elements dividing said enclosure into two end chambers and a center chamber, a box-like compartment located beneath said frame and secured thereto, there being an opening establishing communication between the interior of said box-like compartment and one of said end chambers, there being a second opening establishing communication between the interior of said box-like compartment and said center chamber, one of said end chambers communicating with a source of fresh air and the other of said end chambers communicating with a source of

room air, a filter located between said compartment and said center chamber, a partition in said compartment movable to vary the area of said last-named filter through which fresh air may pass, the remaining area of said last-named filter being in communication with a source of room air, and a motor-driven fan located in said center chamber and receiving its supply of air through said filters.

3. In a device of the class described the combination of a box-like frame having top, bottom, and side portions forming an elongated enclosure, filter elements dividing said enclosure into two end chambers and a center chamber, a box-like compartment located beneath said frame and secured thereto, there being an opening establishing communication between the interior of said box-like compartment and one of said end chambers, there also being a second opening establishing communication between the interior of said box-like compartment and said center chamber, a filter located between said compartment and said center chamber, there being openings connecting one of said end chambers with fresh air and the other of said end chambers with room air, a partition in said compartment, a threaded shaft supported in the walls of said box-like compartment for adjusting the position of the partition in the compartment to filter the area of the last-named filter available for passage of fresh air therethrough, and a motor-driven fan located in said center chamber, said fan receiving its supply of air through said filters.

DEANE E. PERHAM.
